A handwritten signature in cursive ink, appearing to read "James N. McCammon". Above the signature, the word "By" is written, indicating it is a signature of the inventor.

ATTORNEY

UNITED STATES PATENT OFFICE

138,256

DESIGN FOR A WALL TILE

James N. McCammon, Dallas, Tex.

Application October 25, 1943, Serial No. 111,495

Term of patent 14 years

(Cl. D18—2)

To all whom it may concern:

Be it known that I, James N. McCammon, a citizen of the United States, residing at Dallas, in the county of Dallas and State of Texas, have invented a new, original, and ornamental Design for a Wall Tile, of which the following is a specification, reference being had to the accompanying drawing, forming part thereof.

I claim:

The ornamental design for a wall tile, as shown.

JAMES N. McCAMMON.
